(57) **CLAIM**

The ornamental design for a swim platform assembly for boats, as shown and described.

DESCRIPTION

FIG. 1 is a perspective view of a swim platform assembly for boats according to our new and ornamental design in a lowered position;

FIG. 2 is a side view thereof;

FIG. 3 is an opposite side view thereof;

FIG. 4 is a front view thereof;

FIG. 5 is a rear view thereof;

FIG. 6 is a top view thereof;

FIG. 7 is a bottom view thereof; and,

FIG. 8 is a perspective view thereof in a raised position. The broken lines in the drawings illustrate portions of the swim platform assembly for boats that form no part of the claimed design.

1 Claim, 8 Drawing Sheets
